UNITED STATES PATENT OFFICE.

WILLIAM A. MELROSE, OF CHICAGO, ILLINOIS, ASSIGNOR TO ELIZABETH MELROSE, OF DETROIT, MICHIGAN.

COMBINATION TABLE AND IRONING BOARD.

Application filed January 23, 1928. Serial No. 248,885.

My invention relates to the ironing boards and more particularly to that type of ironing boards which are embodied in a table, my main object being to provide a combination of this character which is of a compact nature.

A further object of my invention is to so locate the novel ironing board that the ordinary use of the table is not interfered with while the ironing board is not in service.

A still further object of the invention is to so dispose the novel ironing board that it may be readily exposed and moved to the service position by a simple movement of the table top.

Another object of the invention is to locate the ironing board while in the service position at a position partly overhanging a side of the table, so that full and immediate access may be had to the ironing board without interference by the structure of the table.

A final but nevertheless important object of the invention is to construct the novel combination with a gearing of utmost simplicity, enabling the structure to be produced at little greater expense than the table itself.

With the above objects in view and any others that may suggest themselves in the specification and claims to follow, a better understanding of the invention may be gained by reference to the accompanying drawings, in which—

Figure 1 is a side elevation of the novel combination as applied to a drop-leaf style of table, the remote leaf being shown dropped;

Fig. 2 is a section on the line 2—2 of Figure 1, showing on the left-hand side a dotted line indication of the changed position of the table top for the purposes of the ironing board;

Fig. 3 is a plan view, partly broken away, showing the table in position for the withdrawal of the ironing board to the service position; and

Fig. 4 is a perspective view of a latch detail.

I am aware of the fact that many ironing board and table combinations have been devised in the past to save the necessity of having an extra ironing board or stand where space is limited, but in most devices which have come to my attention, the ironing board

mechanism has been more or less involved, and has required that the table be made of a special construction to accommodate the ironing board. Also, in some cases the development of the ironing board from the table required a great amount of room, so that the ironing board could be considered much in the way of persons passing the table. With these and other deficiencies in mind, it has been my intention to provide a structure of extreme simplicity and compactness while in use either as a table or as an ironing board, and my structure is designed to fulfill the objects contemplated above to the fullest extent.

Referring specifically to the drawings, 10 denotes the sides, 11 the ends, 12 the top, 13 the legs, and 14 the drop-leaves of a typical household table. The design of the table may be of any suitable character, except that the construction of the top 12 be permanent but in part, the greater portion 12^a thereof being separate and adapted to be swung relative to the same through the agency of hinge straps 15 at the ends. Thus, the table top 80 portion 12^a may be swung clear over to assume a position extended from the table proper as indicated by the dotted lines in Figure 2, and full lines in Figure 3. In either case, the portion 12^a forms a continuation of the permanent top 12. When closed, the portion 12^a rests on the table ends 11, but when it is swung over to extended position, it rests on the upper edge of the corresponding—in this case the left-hand—drop-leaf 14. This expedient gives the portion 12^a the necessary support that it may bear the weight of clothes or other articles laid thereon when ironing is to be done, but I may choose to rest the portion 12^a on a 95 projection or shelf suitably positioned, in case I apply the swingable top to a table devoid of drop-leaves.

With the table top portion 12^a swung to extended position as just described, a clear 100 view of the ironing board 16 is had. As noted, this board is of the length of the table, and ordinarily rests in pockets 17 cut down from the table ends 11. The board is reinforced underneath with bearing blocks 16^a for a pair of arches 18 extended longitudinally under the board. These arches are of metal and in the nature of rods, and are formed with terminal bends 18^a which in turn have short outward bends entering the 110

ends 11 of the table. The arches 18 furnish a support for the ironing board in the nature of parallel links, so that the board may be swung up from its inactive position in the 5 pockets 17 to a high position above the table, as clearly indicated by dotted lines in Figures 1 and 2. At this juncture, the bends 18^a at the forward part of the movement strike the legs 13, as indicated in Figure 2, 10 preventing the assembly from swinging forward. Since the assembly has swung beyond the point of its greatest height, the board will find a rest and will be firm when weighted with articles to be ironed or with 15 the iron if it is in operation.

At the time that the board is in service position, the extended table top can still serve to receive articles to be ironed or which have already been ironed, thus providing a 20 handy place for deposit. At the same time, the drop-leaf 14 in the vicinity of the elevated ironing board may be used for the same purpose, when in the position noted in Figure 2. However, if close access to the 25 ironing board is desired, this leaf may also be dropped. It will now be apparent that the elevated ironing board overhangs the side of the table to a marked extent, which enables the operator to stand close to it without 30 interference by the table itself, such as would be the case in the event that the ironing board were to have its service position intermediate of the table area.

When the ironing board is no longer required for use, it may be easily pushed back to the original position beneath the table top, and the extended portion 12^a of the latter swung back to close the table. In such event, I provide an eye 19 on the under side of the 40 portion 12^a which is engageable by a latch hook 20 outside one of the table ends to hold the portion 12^a down against tilting or vibrating movements suffered by the table. Thus, to all intents and purposes, the table 45 is again a complete drop-leaf structure, without any apparent suggestion of its transforming capacity.

While various means may be employed to retain the drop leaves in elevated position, 50 I believe it best to drop a pivotal link 21 from each leaf, curving the link in the direction of the table sides 10. Below each table side I provide a cross rail 22, and attach a vertical plate 23 at a medial point of the side 10 and rail 22 by screws 24 or other suitable means. The plate 23 is formed with a vertical slot 25 through which the link 21 is adapted to move as the corresponding drop-leaf 14 is swung, the bottom of the slot 55 forming a support for the link. As an additional support for the inward swinging of the links I add a spacer board 26 between the rails 22, as clearly shown in Figure 2. Near the inner end of each link 21 I cut a slot 21^a from above, in which is adapted to

fall a bar 27 pivoted at 28 near one end of the rail 22, this bar preferably having its free end inwardly bent as indicated at 27^a to serve as a lever. Thus, when a given drop-leaf is down, the bar 27 merely rests on the 70 link 21; however, when the drop-leaf is swung outwardly the bar falls into a slot 21^a as soon as the leaf has attained the final or horizontal position, the slot 21^a being, of course, positioned to correspond. The leaf 75 is now locked in elevated position, and no attention was required for its mechanism during its swing, as the mechanism operated automatically when the leaf was raised manually. Conversely, to drop the leaf, all 80 that is necessary is to slightly lift the lever end of the bar 27 when one has access thereto from the opening in the table, at which juncture the leaf will drop of itself. However, in case the dropping of the leaf is desired to be done from the outside of the table, the bar itself may just as conveniently be touched in the lifting direction with the finger, in which event the leaf will become 85 released for descent. The gearing for the drop-leaves is noted as being simple, and positive, its main advantage being that it will retain the leaf in horizontal position without permitting it to sag or weaken in any manner due to an imperfect support. The 90 weight of the leaf or contents thereof bears through the link upon the bar 27 from a lateral direction, and the bar in turn lies against the plate 23 which is stout enough to 95 stand any reasonable strain without occasioning any loss of motion or adjustment.

It will be seen that I have provided a simple and very compact structure for the purposes intended. Ordinarily the table can function fully for any purpose intended for it without the suggestion of a handicap offered by the presence of the ironing board feature; on the other hand, when the table has been opened to reveal the ironing board, 105 not a great deal of additional room is required laterally of the table for the accommodation of the extended top thereof. When the ironing board is in service it occupies a comparatively small amount of extra lateral space, so that persons may pass in the region of the table without feeling that any part thereof is in the way. At the same time, the elevated board forms a strong and handy appliance for the work of ironing, and does not require any stand of its own. No levers or other contrivances need 110 be handled to operate the ironing board, and no springs or delicate parts are involved to make the action thereof uncertain or subject to disorder. When the board is not required, it is fully concealed and kept clean, and no special place is required to keep the same. In conclusion, the parts employed are few and simple, and the cost of the table 115 is increased but slightly as compared to the 120 125 130

value of its major features when separately considered.

I claim:

1. A combination table and ironing board comprising a permanent table-top section, a complementary table-top section swingable about the permanent section to an extended position in the same plane from the outer edge of the latter, a support for said complementary section when extended, an ironing board under the complementary section, and means to elevate said ironing board to a service position above said table top section when the complementary section has been swung.
2. A combination table and ironing board comprising a permanent table-top section, a complementary table-top section swingable from the permanent section to an extended position in the same plane from the outer edge of the latter, a drop-leaf with its top edge forming a support for said complementary section when extended, an ironing board under the complementary section, and means to elevate said ironing board to a service position when the complementary section has been swung.

3. A combination table and ironing board comprising a table top, a supporting frame therefor, end members thereon, an ironing board under said top, means for opening a portion of said top along one side of the table, and a pair of swingable parallel links pivoted to the end members of the table for the support for the ironing board and for elevating the same with a lateral motion in the direction of its width and said side, whereby to cause the ironing board to be above the plane of the table when elevated.

4. A combination table and ironing board comprising a table, a top therefor, legs therefor, a portion of the top adapted to swing open, an ironing board under said portion and longitudinal of the table, a pair of parallel links hung from the ironing board and pivoted in the ends of the table, and the legs in one side of the table serving as abutments for the links opposite the same to rest said ironing board in elevated position beyond the highest point in the swing of said links.

In testimony whereof I affix my signature.

WILLIAM A. MELROSE.
